UNITED STATES PATENT OFFICE

CHARLES W. ANDREWS, OF CHICAGO, ILLINOIS, ASSIGNOR TO H. A. BRASSERT & COMPANY, OF CHICAGO, ILLINOIS, A CORPORATION OF ILLINOIS

CHECKER BRICK

Application filed February 18, 1928. Serial No. 255,314.

This invention relates to a new and improved design of checker brick and checker-work for hot blast stoves, and more particularly to a modification or improvement of 5 the designs shown in my prior application, Serial No. 247,570, filed January 18, 1928, jointly with Herman A. Brassert and Albert J. Hulse.

In the prior application above referred to 10 we disclosed a checkerwork construction for hot blast stoves which was particularly adapted for substantially increasing the heating efficiency or transferring of heat in checker brick, and also to increase the heating surface of a given stove. In stoves of usual construction the vertical passageways in the checkerwork are of uniform area throughout their height and this results in a difference of 15 velocity of the gases at different points in the height as the gases increase or decrease in volume during their passage through the stove. In the prior application we disclosed several forms of constructions in which the 20 height of the stove was decreased in the lower portion of the stove by means of additional loose brick placed in the passageways. The form previously developed permitted the use of 25 loose brick of varying sizes so that there might be a plurality of zones in the height of the stove, each zone having different effective 30 passage area. The prior construction involved the use of loose brick both in the passageways formed between the check brick and in vertically extending passageways formed 35 in the brick themselves.

It is an object of the present invention to provide a construction in which the effective passage area through the checker brick is modified by integral portions of the brick.

40 It is a further object to provide a construction in which a transverse web extends across the passageway in the brick and in which different brick may be made with webs of different thickness for use in different zones in 45 the checker construction.

It is an additional object to provide a construction in which integral means are also provided for modifying the area of the passageways between the brick.

It is also an object to provide a brick which 50 may be readily constructed with usual brick making machinery at a minimum of cost and which may be readily installed in checker-work construction.

Other and further objects will appear as 55 the description proceeds.

I have illustrated in the accompanying drawings certain preferred embodiments of my invention, in which—

Figure 1 is a fragmentary transverse section 60 through the checker brick embodying my brick;

Figures 2, 3, 4, 5, 6, 7 and 8 are views similar to Figure 1 but showing different modified forms of brick.

Referring first to Figure 1, the brick 11 are 65 octagonal in cross section, being provided with four sides 12 between which are placed the alternate four sides 13. The sides 12 are materially greater in width than the sides 13. 70 The brick are built up so that the sides 13 contact with adjacent brick and the sides 12 form passageways 14 between the brick. The brick are provided with vertically extending passageways 15 which are divided by the 75 transverse web 16, shown in section in Figure 1. The side faces of this web are formed by sloping surfaces in angular relation which meet at the thickened central portion 17. As shown in the figure, brick placed below the 80 brick shown in section may be provided with thicker webs 18. These webs 18 are of the same general form as the web 16 but the side faces are formed on such angles as to make the web thicker at its central portion.

85 The passages 14 contain the loose brick 19 which are formed with their ends 20 substantially conforming to a corner of the passageway. The side faces of the brick meet on the line 21 and these faces are at such an 90

angle as to give the cross section of the brick substantially the form of the cross section of the web 16 of the brick 11. As shown in Figure 1, the lower loose brick 22 may be thicker than the brick 19.

5 The form of construction shown in Figure 2 is similar to that in Figure 1 except that the passages 23 between the brick 11 have no loose brick therein. The brick 11 shown in cross section are identical with the brick 11 of Figure 1. Brick 24, located below the brick 11 are similar in form to the brick 11 with the exception that instead of flat faces 12, they have rounded faces 25 which extend into the vertically extending passageways 23. In Figure 3 the brick 11 are shown as superposed on brick 26 which have more pointed projections 27. These projections as shown in the figure, extend further into the passageway 28 than do the projections 24 of Figure 2. In Figure 4 the brick 11 are superposed on brick 29 which are formed with extended faces 30 which are corrugated in form. These corrugations afford an increased contact area 25 for the gases passing through the passageways 31. In Figure 2 the brick 24 have thickened webs 32 which are thicker than the web 16 of the brick 11. Similarly, in Figure 3, the brick 26 have thickened webs 33 and in 30 Figure 4 the brick 29 have thickened webs 34.

The forms of construction shown in Figures 5 to 8 are provided with lugs or extensions which render unnecessary the use of the loose brick which are used in the form 35 of construction shown in Figure 1.

Referring first to the form of construction shown in Figure 5 the brick 36 are formed with eight sides, four wider sides 37 and four narrower sides 38. The narrower sides are in contact and the wider sides 37 form the passage 39 when the brick are built up in a checker work construction.

Two of the wider sides 37 are provided with the longitudinally extending flanges 40. 45 These flanges have the enlarged ends 41 and the reduced necks 42 where the flanges join the main body of the brick. The central portion of the brick as provided with the openings 43 which are separated by the web 44. This web 44 is similar in form to the web 16 of the form of construction shown in Figure 1. Brick lower in the structure of Figure 5 are provided with thicker webs 45 similar in general contour to the webs 44. The two openings 43 and the web 44 may be considered as a cylindrical opening divided by a transverse web. The brick are placed in the checker work as shown in Figure 5 so that two flanges 40 will co-operate

60 with each other and these two flanges together form a structure approximating in contour that of the web 44. The passageways 39 are thus divided in a manner similar to the division between the passageways 43. 65 The lower brick having the wider integral

web 44 may also be provided with wider flanges 46 as shown in the drawing.

The form of construction shown in Figure 6 is similar to that of Figure 5 with the exception that all four of the wider faces 47 of the block 48 are provided with the flanges 49. These flanges 49 divide the passageways 50 into four smaller passages. Wider flanges 51 may be used in the lower brick.

In the form of construction shown in Figure 7 the brick 52 are provided with the shorter flanges 53 which are of such length as to divide the passageway 54 into five substantially equal passage areas. Wider flanges 55 may be used on brick in the lower portion of the structure.

The form of construction shown in Figure 8 has the brick 56 provided with flanges 57 on only two of the wider faces 58. As shown in the drawing, lower brick may be placed at right angles to upper brick so that the opposed flanges 59 of lower brick form transverse webs at right angles to the webs formed by the flanges 57 of the upper brick. It will be understood that a number of successive layers of brick may be placed with their flanges running in the same direction. All of the forms of construction shown in Figures 5 to 8 provide means for progressively decreasing the effective area of the passageways between the brick, as well as those extending through the brick, without the use of the loose brick which are required in the form of construction shown in Figure 1.

While in each figure of the drawing there have been but two forms shown giving but two different area of passageways, it will be understood that the webs, flanges and loose brick may be made in a plurality of thicknesses. The various forms may be used alone or in combination. For example, the form of brick 26 of Figure 3 might be used for a lower checker section and have superposed thereon the brick 24 of Figure 2 for an intermediate section and the brick 11 of Figure 1 for an upper intermediate section. The brick formed entirely without webs or flanges may be used in the upper section and such section may have no loose brick or extensions into the passageways formed between the brick.

While I have illustrated certain preferred embodiments of my invention, it will be apparent that the invention is capable of further modifications with which to meet the varying conditions and requirements, and I contemplate such modifications as come within the spirit and scope of the appended claims.

I claim:

1. A checker brick having a longitudinal opening extending therethrough and an integral web extending transversely of the opening, said web being gradually thickened toward its central transverse portion.

2. A checker brick octagonal in form with

- four alternate faces of materially less width than the remaining four faces and having a central opening therethrough and an integral transverse web in said opening, said web having angular surfaces in cross section, being thicker at its intermediate transverse portion. 70
3. A checker brick having a longitudinal opening extending therethrough, an integral web extending transversely of the opening, said web being gradually thickened toward its central transverse portion, said brick having lateral faces and longitudinal flanges on certain of said faces. 75
- 15 4. A checker brick octagonal in form with four alternate faces of materially less width than the remaining four faces and having a central opening therethrough, an integral transverse web in said opening, and longitudinal flanges on the four faces of greater width. 80
- 20 5. A checker brick octagonal in form with four alternate faces of materially less width than the remaining four faces and having a central opening therethrough, an integral transverse web in said opening, said web having angular surfaces in cross section, being thicker at its intermediate transverse portion, and longitudinal flanges on the four faces of greater width each said flange being similar in contour to one half of a transverse web. 85
- 25 6. A checkerwork construction comprising a plurality of octagonal brick built up to form vertically extending passageways therebetween, integral flanges on said brick extending into said passageways, another series of vertical passageways in said brick, and integral webs extending transversely of 90
- 30 35 said passageways. 95
- 40 7. A checkerwork construction comprising a plurality of octagonal brick built up to form vertically extending passageways therebetween, integral flanges on said brick extending into said passageways, another series of vertical passageways in said brick and integral webs extending transversely of 100
- 45 50 said passageways, said webs being similar in contour to a pair of adjacent flanges. 105
- 55 60 8. A checkerwork construction comprising a plurality of octagonal brick built up to form vertically extending passageways therebetween, integral flanges extending into all said passageways in the lower portion of 110
- 65 70 the structure, another series of vertically extending passageways in the octagonal brick, and integral transverse webs in all passageways in the brick in the lower portion of the structure. 115
- 75 80 9. A checkerwork construction comprising a plurality of octagonal brick built up to form vertically extending passageways, larger integral flanges extending into the passageways in a lower section of the structure, smaller integral flanges extending into 120
- 85 90 125
- 95 130
